(**) Term: **14 Years**

(57) **CLAIM**

(21) Appl. No.: **29/142,649**

The ornamental design for an enclosure for an electrical adapter, as shown and described.

(22) Filed: **May 30, 2001**

DESCRIPTION

(30) **Foreign Application Priority Data**

Dec. 1, 2000 (GB) 2097843

(51) **LOC (7) Cl.** **13-03**

(52) **U.S. Cl.** **D13/154; D3/273**

(58) **Field of Search** D3/273, 302, 300,

FIG. 1 is a front elevational view of an enclosure for an electrical adapter in an extended condition showing my new design, with a rear elevational view being identical thereto; FIG. 2 is a left side elevational view thereof, with a right side elevational view being identical thereto;

D3/298; 206/702; D13/154, 155, 199; 174/50,

FIG. 3 is an end elevational view from a first end thereof, with an end elevational view from a second end thereof being identical thereto;

67, 65 R, 135; 439/142, 501, 367; 220/3.8,

FIG. 4 is a front elevational view of the enclosure for an electrical adapter in a retracted condition, the rear elevational view thereof being identical;

3.7, 3.94

(56) **References Cited**

FIG. 5 is a left side elevational view of FIG. 4, the right side elevational view thereof being identical;

U.S. PATENT DOCUMENTS

FIG. 6 is a perspective view of the enclosure for an electrical adapter shown in the extended condition; and,

FIG. 7 is a perspective view of the enclosure for an electrical adapter shown in the retracted condition.
